Inventor;

C. W. Howard

UNITED STATES PATENT OFFICE.

CHAS. W. HOWARD, OF PHILADELPHIA, PENNSYLVANIA.

IMPROVED CLOTHES-LINE CLAMP.

Specification forming part of Letters Patent No. 58,419, dated October 2, 1866.

To all whom it may concern:

Be it known that I, CHARLES W. HOWARD, of the city of Philadelphia, in the State of Pennsylvania, have invented a new and useful Device for Supporting Clothes-Lines; and I do hereby declare that the following is a full, clear, and exact description of the construction and operation of the same, reference being had to the accompanying drawing, making a part of this specification, and to the letters of reference marked thereon.

The nature of my invention consists in constructing and combining together a bent metallic lever and a hooked plate, so that, when the device is permanently secured to the usual upright post and the clothes-line applied, the tensional strain of the latter will cause the same to be pinched between the lever and the plate, in such a manner that each portion of the line between the posts will be supported independently of any other portion, and so, also, that the greater the strain upon the line the more securely will it be held by the device, whereby not only a perfectly reliable fastening for the line is provided, but greater facility afforded in putting up and taking down the line.

The drawing represents both a front and a side view of the device, fixed to the supporting-posts and the line applied, like letters of reference indicating the same parts when in both views. In either, therefore, A is the bent lever; B, the hooked plate; C, the post, and D the clothes-line.

The plate B has two hooks, the one, b^1 , projecting upward, the other, b^2 , downward, from respective arms b^3 b^4 , which extend forward half an inch, more or less, from the ends of the plate B, as shown in the drawing. The middle or flat portion of the said plate B is permanently secured, by means of the screws e , to the side of the upper end of the post C.

The lever A is a flat bar, which is secured so that it can be easily vibrated on the plate B by means of one of the screws e' , which passes through it and forms its fulcrum-pin.

The shorter end of the lever A has an arm, a^1 , which projects forward so that its one side

can be brought into contact with the inner corner edge of the arm b^3 . The longer or power end of the lever A has also an arm, a^2 , which projects forward and is turned upward at its end a^3 , and leaves a space of an inch, more or less, between it and the projection b^2 when the shorter end a^1 of the lever is in contact with the projection b^3 .

The clothes-line D is applied by passing its end d' downward between a^1 and b^3 , and then carrying the line across over the arm b^3 , then down under the arm a^1 and over the arm a^2 of the lever A, and drawing the latter downward thereby, so as to cause the arm a^1 to pinch the line D between a^1 and b^3 , and, finally, stretching the line D tightly across under the arm b^4 , and carrying it to the next post C¹, and securing it tightly by passing it across over the arm b^3 , and then down between a^1 and b^3 , and closing the arm a^1 of the lever A against it, thus causing the tensional strain of the said stretched portion of the line to keep the lever closed on it so as to retain it, as shown in the drawings. The free portion of the line may be now passed over the power end of the lever just closed, and then under the arm b^4 to the next post, and so on for the rest of the line.

It will be seen that the more the line D is loaded or stretched the tighter it will be held by the device; that each section so strained will be retained independently of any other section; and that the line can be put up or taken down with greater facility and rapidity than heretofore—a matter of considerable importance in cold or winter weather.

Having thus fully described my invention and shown its utility, what I claim as new, and desire to secure by Letters Patent, is—

A device for supporting a clothes-line, consisting of the pieces A and B, or their equivalents, constructed and combined to operate together so as to pinch and hold the line by the tensional strain of the latter, substantially as described and set forth.

C. W. HOWARD.
